BOX OR COVER ENDING MACHINE

Walter P. Osgood, Malden, Mass., assignor to
 Boston Machine Works Company, Lynn, Mass.,
 a corporation of Massachusetts

Application June 17, 1941, Serial No. 398,447

8 Claims. (Cl. 91—51)

This invention relates to a coating mechanism, and more particularly to a mechanism designed for use in applying a coating or film of liquid cement to certain areas of cardboard box blanks in the course of making up boxes and covers from such blanks. The coating mechanism herein described is intended for use in conjunction with pressing mechanism such as is described in my copending application Serial No. 448,366, filed June 25, 1942, such pressing mechanism being designed to press the coated areas of the box or cover blank against other areas to promote firm adhesion.

The various features of the present invention will be readily understood from an inspection of the accompanying drawings illustrating the best form of the invention at present known to the inventor, in which,

Fig. 1 is a detail view in sectional plan of the coating part of the machine, the pressure roll having been taken away to show underlying parts;

Fig. 2 is a detail view in sectional elevation on the line 2—2, Figure 1;

Figure 3 is a detail view in right-side sectional elevation on the line 3—3, Figure 1;

Figure 4 is an enlarged detail view in right-side sectional elevation showing the bearings for the shaft upon which the pressure roll is mounted;

Figure 5 is a detail view in front sectional elevation on the line 5—5, Figure 3;

Figure 6 is a detail view in front sectional elevation on the line 6—6, Figure 3, and

Figure 7 is a detail view in front sectional elevation of a portion of the drive for the pressing roll.

The embodiment of the invention illustrated in the drawings comprises a horizontal work table 38 along which the operator may slide successive box or cover blanks to ride over a doctor 39 which is secured to the right-hand rim of a trough 40a (Figure 6) into the bite between a lower coating roll 41 and an upper pressure roll 42. From the delivery side of these rolls the blanks pass out over the left-hand rim of the trough 40a. This trough projects from and communicates with a heated glue pot 40 (Figure 3). The coating roll 41 which is composed of three solid pieces of steel 43, is secured to the forward portion of a shaft 44 journalled in stationary bearings 45 and 46 journalled in the upper portion of the hot glue pot 40. The shaft 44 is provided with a belt pulley 47 which is driven by a belt 48 on the small pulley 49 secured to the

armature shaft 50 of an electric motor 51. The motor 51 is bolted to a platform 52 which is secured in the upper portions of three rods 53, the lower portions of which are secured to a platform secured to a lateral extension 54 of a ring 55.

The glue pot 40 is supported by a jacket 106 which is mounted on a ring 56 secured eccentrically, (Figure 1), on a rod 57 depending therefrom. The rod 57 passes vertically through the duplex ends 60 of a girder 61, having opposite ends like the ends 60 adjustably secured to a vertical standard (not shown) which may be conveniently secured to the frame of a pressing mechanism.

The pressure roll 42 (Figure 3), is a piece of a "Bakelite" tube 67, the front end of which is mounted on a cylindrical bushing 68 with the front end of the bushing held in engagement with the front end of the tube. The bushing 68 is secured to a shaft 69, the front end of which is mounted in a journal 70 secured to the front end of a hood or canopy 71 which supports the roll 42 and is rockably mounted so that the roll 42 can yield upwardly away from the roll 41 to accommodate work of different thicknesses. The rear end of the pressure roll 42 is secured to the peripheral edge of a cylindrical bushing 72 secured to the shaft 69.

The rear end of the shaft 69 passes freely through a collar 73 mounted in the canopy 71. A gear 74 is secured to the end of the shaft 69 adjacent the collar 73. The center portion of the shaft 69 is journalled in a bearing mounted within the canopy 71, there being a collar 75 secured to the shaft 69 interposed between the bearing and the bushing 72. For proper operation it is essential that the rolls 41 and 42 be parallel. As the rolls are independently supported, accurate parallelism of their shafts cannot be depended on in actual manufacture of the machines. Hence provision is made for sufficiently adjusting the axis of the roll 42 so that it can be made accurately parallel with the axis of the roll 41. As can be seen in Figure 3, the outer or front portion of the canopy 71, which longitudinally spans the roll 42, is so formed as to be capable of being slightly sprung with respect to the heavier body portion of the canopy. Suitable adjustment of the roll 42 is made by means of a pair of truss rods 76 one of which is shown in Figure 3. The ends of these truss rods are anchored in upstanding ears which rise from the canopy 71 immediately above the shaft bearings adjacent to the ends of the

roll 42. The anchoring means consists of nuts 77 and 78 threaded on the rods 76, by manipulation of which the outer end of the roll 42 may be adjustably sprung up or down to bring the axis of the roll into exact parallelism with that of the roll 41. In order to avoid undesirable binding of the shaft 69 when it has thus been sprung with the roll 42, the journals (Figure 4) adjacent to the ends of the roll 42 are externally tapered so that they can adjust themselves to slight changes in the shaft axis. These journals are held against rotation and axial shifting by suitable means such as screws 79 which permit them to rock slightly.

The glue pot 40 is provided with a cover 81 which is hinged to the pot as at 80. The canopy 71 is hinged to the pot cover 81 on an axis parallel to the roll axes and on the delivery side of the rolls, a shaft 86 serving as the hinge pin. The shaft 86 is journaled in a pair of bearing members 81a which extend up from and are a part of the cover 81. When the machine is in operation, the cover 81 is locked shut by a pair of screws 82 extending from the front wall of the pot 40 through notches 83 in the front margin of the cover and provided with wing-nuts 84 as shown in Figures 1 and 5. Pinned on the shaft 86 are two collars 87 and 88 between which is confined a gear 89 rotatable on the shaft. The gear 89 meshes with the gear 74 and also with another gear 90 which is mounted on a shaft 91 journaled in a pair of bearing members 92 which extend up from the glue pot cover 81. Also mounted on the shaft 91 is a gear 93 which meshes with the pinion 94 on the shaft 44.

Since the shaft 69 (which is supported by the canopy 71) is parallel to the shaft 86 about which the canopy is hinged, the gear 74 always remains meshed with the gear 89 for any position of the canopy 71.

As is evident from Figure 5, during the operation of the mechanism the upper roll 42 rotates in a clockwise direction, the lower roll 41 and the shaft 86 rotating in a counter-clockwise direction. If anything should tend to hold the upper roll against rotation, such as a piece of work of extra thickness wedged in the bite between the rolls, the counterclockwise rotation of the pinion 89 (Figure 7) tends to elevate the pinion 74 and thus to lift the roll 42 away from the roll 41. When a piece of work is fed between the rolls 41 and 42, the upper roll 42 yields upwardly against the weight of the canopy 71 and all the parts carried thereby. Preferably the downward pressure of the canopy 71 is augmented by additional means such as a scroll spring 97 one end of which is caught in a slot 96 in an extension 95 of the collar 88, the other end of the spring being attached to the canopy 71 as at 98. A definite adjustable limit can be put on the upward yielding movement of the roll 42 by means of a screw 99 threaded into the cover 81 and locked in adjusted position by a lock-nut 100. The screw has a head 101 which is engaged by a notched ear 102 on the canopy 71 when the canopy reaches the permissible limit of its upward movement. The downward movement of the canopy 71 and roll 42, or in other words the clearance between rolls 41 and 42, is adjustably limited by a screw 103 (Figures 1 and 6) which is set into the wall of the glue pot 40 and is engaged by the canopy 71 at a point remote from the hinge axis 86. Provision is made of means for preventing actual contact

between the rolls 41 and 42 in case the limit screw 103 is set down too far. Such means comprises a stop element 85 (Figure 3) which may consist of a screw secured in the pot cover 81 and engageable by the canopy 71 before the roll 42 can touch the roll 41.

The tension of the spring 97 can be regulated by angular adjustment of the normally stationary shaft 86. To turn the shaft 86 a suitable tool 10 may be inserted in a hole 104 in the shaft for use as a lever, the shaft being held in adjusted angular position by means of a setscrew 105 (Figure 5).

The pot 40, containing the glue which has a water solvent, is surrounded partially by a jacket 106 (Figure 5), of hot water. The water is heated by a heating element 107 extending horizontally from a control box 108 secured to the exterior of the jacket 106. A thermostat 109 extends horizontally from the control box. After the glue is heated by the hot water, it is fed to the trough 40a by a horizontal feeding device 110 (Fig. 3), secured to a shaft 111 which is packed from the water jacket 106 and is driven by a belt 112 which passes around a belt pulley 113 on the shaft 111 and a smaller belt pulley 114 on the armature shaft 50 of the motor 51. Excess glue delivered by the feed screw 110 spills back into the pot 40 over a vertically adjustable dam located above the left-hand end of the feed screw 110 (Figure 3).

The water jacket 106 is provided at its bottom with four screws 115 (Figures 1 and 2), by which the water jacket and its supported glue pot 40 are secured to the ring 55. The glue pot 40 is provided with a cover plate 115a (Figure 3), which provides for the removal of debris from the pot, and with a pipe 116, suitably packed from the jacket 106, which provides for removing the glue from the pot. A drain plug 117, secured to the jacket 106, is used to drain the water therefrom.

The doctor 39 (Figure 6), is a sheet of scarfed metal adjustably mounted on the right-hand rim of the trough 40a substantially in engagement with the upgoing side of the coating roll. A portion of the gage 37 constitutes the outer end wall of the trough 40a and is provided with screws 117a (Figure 3), which secure thereto a journal 118 for the coating roll shaft 44. As shown in Figure 3, the outer end of the coating roll 41 is hollowed to receive and surround the journal 118. The end of the roll bears at its periphery against the gage 37 and thus prevents access by glue in the trough 40a and on the roll 41 to the journal 118. The table 38 is a stationary piece of metal secured to the gage 37 by brackets 119 (Figure 1).

The coating part of the machine is provided with a "Sirocco" fan 120 (Figure 3), which is mounted on the end of the armature shaft 50 of the electric motor 51 and which blows cold, or atmospheric, air through the stationary outlet 121 into a pipe 122 having one end thereof secured in position on the movable frame 71 by a small coupling 123. The coupling 123 delivers the air blown by the fan 120 centrally upon the pressure roll 42. On its right side (Figure 6), the canopy 71 is provided at its lower end with a curved guard plate 120a which is coaxial with the roll 42 and has its bottom spaced from the doctor 39. The guard 120a also acts as a guiding means to conduct the air delivered by the coupling 123 to the bite between the rolls 41 and 42. The outlet size of the coupling 123 is suffi-

cient to deliver air to the bite along the length of the roll 42. The roll 41 is a wet roll while the roll 42 is a dry roll, but comes into proximity with the coating roll 41 when the work is coated and is removed from the coating part of the machine. The fan 120, by blowing atmospheric air upon the pressure roll 42, which is conducted to the bite between the coating roll 41 and the pressure roll 42, provides means for preventing the condensation thereon of vapors coming from the heated coating compound.

Nothing herein explained is to be interpreted as limiting the various features of the present invention in the scope of its application to use in connection with the particular machine or the particular mode of operation or both selected for purposes of illustration and explanation. While the particulars of construction herein set forth are well suited to one mechanical form of the invention and to the use to which it is put, it is not limited to this use, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new, is:

1. In a coating machine, a trough having an end wall, a journal secured within said trough to said end wall, a shaft having one end rotatable in said journal, and a roll mounted on said shaft and having an end hollowed to receive and surround said journal, said roll end being in engagement with said end wall of the trough.

2. In a coating machine, a pair of rotatable rolls, means for supporting said rolls one above the other in closely spaced relation, means for supplying a film of moist coating material to the lower roller, and means for maintaining an air flow over the surface of the upper roll whereby to prevent precipitation of moisture thereon.

3. In a coating machine, a pair of rotatable rolls, means for supporting said rolls one above the other in closely spaced relation, means for maintaining a film of moist coating material on the lower of said rolls, a canopy over the upper roll, and means for maintaining an air flow under said canopy and against said upper whereby to prevent condensation of moisture on said upper roll.

4. In a coating machine, a pair of rotatable rolls, means for supporting said rolls one above the other in closely spaced relation, the support means for the upper roll including a canopy over said upper roll having bearings for said upper roll, means on said canopy for adjusting the axis of said upper roll, means for supplying an air flow between said canopy and upper roll, and means for maintaining a film of moist coating material on said lower roll.

5. In a coating machine, a pair of rotatable rolls, means for supporting said rolls one above the other in closely spaced relation, said means including stationary bearings for the lower roll, a canopy over said upper roll hinged on an axis

parallel to the axes of the rolls, bearings for the upper roll on the under side of said canopy, adjustable stop means for limiting the rocking movement of said canopy about its hinge axis whereby to regulate the spacing between said rolls, and means for driving said rolls at equal peripheral speeds and in opposite directions.

6. In a coating machine, a pair of rotatable rolls, means for supporting said rolls one above the other in closely spaced relation, and means for driving said rolls at equal peripheral speeds and in opposite directions so as to feed work through the nip of the rolls to the delivery side thereof, said supporting means including stationary bearings for the lower roll, a canopy over the upper roll hinged on an axis parallel to the roll axes and offset on the delivery side of the rolls, and bearings for the upper roll on the under side of said canopy, said driving means including a pinion coaxial with the upper roll and rotatable about the hinge axis of the canopy and in mesh with the first-mentioned pinion and common means for driving said lower roll and said second pinion.

7. In a coating machine, a pair of rotatable rolls, means for supporting said rolls one above the other in closely spaced relation, means for driving said rolls at equal peripheral speeds and in opposite directions so as to feed work through

30 the nip of the rolls to the delivery side thereof, said supporting means including stationary bearings for the lower roll, a canopy over the upper roll hinged on an axis parallel to the roll axes and offset on the delivery side of the rolls, and bearings for the upper roll on the under side of said canopy, said driving means including a pinion coaxial with the upper roll and rotatable therewith, a second pinion rotatable about the

35 hinge axis of the canopy and in mesh with the first-mentioned pinion and common means for driving said lower roll and said second pinion, and spring means acting on said canopy in a direction to press the upper roll toward the lower roll.

8. In a coating machine, a pair of rotatable rolls, means for supporting said rolls one above the other in closely spaced relation, means for driving said rolls at equal peripheral speeds and in opposite directions so as to feed work through

50 the nip of the rolls to the delivery side thereof, said supporting means including stationary bearings for the lower roll, a canopy over the upper roll hinged on an axis parallel to the roll axes and offset on the delivery side of the rolls, and bearings for the upper roll on the under side of said canopy, said driving means including a pinion coaxial with the upper roll and rotatable therewith, a second pinion rotatable about the

55 hinge axis of the canopy and in mesh with the first-mentioned pinion and common means for driving said lower roll and said second pinion, means for maintaining a film of moist coating material on the lower roll, and means for maintaining a substantial air flow between said canopy and upper roll to prevent condensation on said upper roll.

WALTER P. OSGOOD.
